METHOD OF DISTILLING TAR

Stuart Parmelee Miller, Englewood, N. J., assignor to The Barrett Company, New York, N. Y., a corporation of New Jersey

Application March 23, 1928. Serial No. 263,990

8 Claims. (Cl. 202—30)

This invention relates to improvements in the distillation of tar, tarry oils and pitch and includes a new method of distillation as well as improved apparatus therefor. Although the invention is applicable to the distillation of tar, etc., with other coal carbonization or gasification gases, it will be described more particularly as applied to coke oven operation.

5

In the ordinary operation of by-product coke ovens, the gases produced by the coking operation pass from the individual ovens thru uptake pipes and goose-necks to a collector main common to the ovens of the battery. The gases, commonly known as "foul" gases, leave the ovens at high 10 temperatures, for example, at 600° to 700° C., or higher, and carry a considerable proportion of pitchy material, tars and oils as well as solid particles of coke, dust, etc. Ordinarily, the gases are cooled by the application of sprays of ammonia liquor or ammonia liquor and tar in the collector main, or by circulating ammonia liquor and tar thru the main, the heat in the gases being thereby dissipated and lost. The rapid cooling causes separation of tar containing heavier 15 oils in the collector main. Further cooling is effected in the cross-over main which connects the collector main to the condensing system and additional tar may be separately recovered from this part of the system. In the coolers or condensers light tars or tarry oils are separated.

20

The tars and tarry oils are blended and are ordinarily shipped from the coke oven or other coal distillation plant to a tar distillation plant for distillation and separation of the oils, and the 25 production of pitches of varying quality. Handling costs, freight charges and distillation costs, including fuel, capital and maintenance expense for the special equipment required for distillation, add to the cost of the tar distillation product.

30

According to the present invention, high temperature coal carbonization gases are admitted under the surface of a body of pitch, tar or oil and by bubbling up thru it the hot gases not only 35 effect distillation but also agitate the body of material causing a continual change of the surface exposed to the hot gases.

The material which is to be distilled according to the present invention, may be coal tar produced at coke oven plants or gas house tar 40 produced at gas retort plants (vertical, horizontal, or inclined), water gas tar, or tar or tarry oil from another source or pitch resulting from the partial distillation of tar. Such tars frequently contain a considerable percentage of

water intimately admixed or combined therewith, particularly where water or ammonia liquor is employed for separating and condensing the tar constituents from the coal distillation or other gases, and such tars may, if desired, be dehydrated before being distilled according to this invention, or may be dehydrated as part of the process.

50

The hot coal distillation gases leaving coke ovens, gas retorts, etc., carry with them solid impurities, such as free carbon, coal dust, etc. The gases also contain in suspension very finely divided particles of tar known as "tar fog". On bringing this gas into contact with liquid in the still, such entrained solids and liquids are removed 55 to a greater or less extent. When the gases are bubbled up thru the liquid as fine bubbles, the surface of contact is large and the scrubbing action of the liquid on the gases is greater than when the gases are admitted to the still as larger 60 bubbles. The depth of liquid thru which the gases pass is another factor affecting the thoroughness of the scrubbing.

65

The gases which are passed thru the body of tar or oil, to effect the distillation of the tar or oil, keeping it in motion continuously presenting new surfaces from which vapors arise, are the hot gases produced by a coal carbonization or gasification operation. The hot gases may be hot coke oven gases or hot retort gases or hot water 70 gas, etc. In the case of hot coke oven gases, for example, the gases escape from the coke ovens at a temperature, for example, from 600-700° C., or even higher in some cases, and these gases, after minimum, or at least regulated cooling in 75 the collector main, may be used for distillation by passing them under the surface of the tar or oil to be distilled and allowing them to bubble up thru the body of liquid. The high temperature gases withdrawn from gas retorts, water 80 gas retorts, producers, etc., may be used in a similar way to effect distillation.

85

The mains connecting the coke ovens, retorts, or other coal carbonization apparatus as well as the still itself, may advantageously be insulated. 90 The still is preferably placed adjacent to or even upon the top of the carbonization apparatus to minimize the amount of heat lost by radiation.

95

According to the present invention, the hot gases may advantageously be passed up thru a considerable depth of the liquid to be distilled. The liquid may in addition be mechanically agitated if desired. The efficiency of the operation is improved by securing prolonged contact of 100 the gases with the liquid by introducing the gas 105

in sub-divided form and by passing the sub-divided gases up thru a considerable depth of the liquid. In operating in this manner, the gases are kept in contact with the liquid for a prolonged period of time and more effective agitation of the body of the liquid is secured. The pressure required to force the gases thru the body of tar or oil increases with increase in the depth of liquid thru which the gases must pass. In actual operation the proper relation between the various factors must be adjusted in such a way as to give the desired efficiency of operation under the particular conditions presented.

The depth of tar or oil in the still may be varied. If the gases are admitted into the still near the bottom so that the depth of liquid in the still is only slightly greater than the depth of liquid thru which the gases pass, the liquor in the still will be thoroughly agitated. Although this is the preferred method of operation, it is possible, on the other hand, to provide a body of tar or oil for distillation which may be of a much greater depth in the still than the depth of tar or oil thru which the gases pass.

The gases may be conducted into the body of liquor to be distilled thru small openings in a pipe or other distributing means submerged in the contents of the still, or the gases may be admitted into the still, thru openings in the bottom of the still itself. Preferably, the gas is admitted to the still thru a multiplicity of small perforations in suitable distributing means in order that the gas may be divided into many small streams which will bubble up thru the contents of the still thereby producing greater surface contact between the gas and the contents of the still than if a fewer number of streams of gas were provided. Any suitable means for causing the gas to bubble up thru the body of liquor to be distilled may be utilized. Pressure may be applied to the gases and vapors in the still, or a reduction in pressure may be maintained above the body of tar or oil in the still.

The still may be of any suitable shape. In the drawings the still is shown as a cylindrical tank. The still is preferably insulated. Pressure may be applied by means of an ordinary exhauster placed between the oven or retort, etc., and the still, or an exhauster or pump may be situated beyond the still to create a vacuum sufficient to draw the gases thru the still.

This invention is well adapted for continuous operation. When operating on this basis, tar or oil is supplied and unvolatilized residue is withdrawn continuously or at frequent intervals and the rate of addition to and withdrawal from the still is at all times regulated so as to maintain the level of liquor in the still approximately constant.

The liquid to be distilled may be pre-heated either by direct or indirect contact with the hot gases as they leave the still or heat from any other source may be used for pre-heating. By controlling the time of contact between the liquor and the gases and regulating the quantity of each, and properly controlling other factors, such as the temperature of the liquid and gases admitted to each still, etc., the distillation effected may be controlled.

Where more than one still is employed the gases leaving several stills may be combined and passed thru a single condensing unit or the gases from each still may be treated separately to recover distinct products which may be of pre-determined boiling range. The non-volatilized residue from

several stills may be combined or a distinctive residue may be collected from one or more individual stills, which, by proper manipulation, may have a predetermined boiling range or other desired property or properties.

For example, when several stills are employed and oil, for example is passed thru the stills in series, and subjected to fresh hot gases, the gases leaving each still may be passed thru a separate condensing system so that a low boiling oil will be condensed from the vapors carried by the gases leaving the first still in the series and higher boiling fractions condensed from the other stills.

By drawing off a portion of the residue from the first still into a separate container and passing the balance into the second still of the series, a residual oil of wide boiling range with a predetermined lower limit may be recovered. Residues of less wide boiling range may be drawn from the succeeding stills.

Various arrangements of stills, hot gas mains and recovery systems permit a variety of operations to be carried out utilizing the general method of this invention.

Although the invention is of broader application, it will be described particularly in connection with coke oven operation. The gas employed for the distillation may be withdrawn at practically its maximum temperature as it comes from the coke ovens, or the gas may be employed at a somewhat lower temperature.

Where the gas is not to be used at or near its maximum temperature, the temperature of the gas may be regulated by the treatment to which it is subjected prior to its use in the distillation operation. The gas may be sprayed with ammonia liquor in the goose-neck and in the collector main, or it may be sprayed with tar or oil in the goose-neck or in the collector main, or it may be sprayed with a mixture of the two, or in both the goose-neck and collector main, and the gas thus cooled to a regulated lower temperature before use for distillation.

Due to the greater specific heat and heat of vaporization of water, spraying with water or ammonia liquor produces a greater cooling effect on the gases than spraying with an equal amount of tar or oil. By regulating the quantity of the water or tar, etc., sprayed in the gases prior to their passage up thru the body of tar or oil to be distilled, the temperature of the gases used for the distillation can be controlled. The temperature of the gases may likewise be controlled by regulating the temperature of the spray. By limiting the amount of cooling, the gases can be employed at a regulated high temperature, such that they have a rapid distilling action in the still.

The temperature and amount of the gases used may be regulated according to the distillation which is to be carried out. If light tarry oils or light tars only are to be distilled, the temperature of the gases used in the distillation need not be as high, or the amount of the gases employed need not be as great, as when higher boiling oils are to be distilled from tar or from pitch.

Where maximum distillation is desired, the gases are employed at practically their maximum temperature, or with only such cooling as is unavoidable or incidental to conveying the gases from the ovens or retorts to the still. By insulating the gas lines to the still the gases can be kept, e. g., at a temperature of 300° C., or 400° C., or 500° C., or higher. With the still located on the top of the coke oven block in close proximity to

the uptake pipe, the gases can be employed at a temperature approximating that at which they leave the uptake pipes. By using such high temperature gases, rapid heating and distillation can be effected, and pitches of high melting point produced, as well as high yields of oils, including high boiling oils.

In the operation of a coke oven the gases produced are not of uniform composition. At the start of the coal distillation process, oils, etc., are liberated from the coal in large quantities and the first gases given off are rich in volatile products. The gases given off during the latter part of the coal distillation, for example, during the last thirty percent of the operating time under normal conditions, contain a less percentage of condensable constituents than the richer gases given off during the first part of the distillation, and are known as lean gases.

There is in many cases an advantage in using either the rich gases or lean gases separately in distillation of tar, according to the present invention. For example, lean gases are capable of taking up a greater quantity of oil and other vapors per unit volume of tar or oil thru which they pass than an equivalent amount of a "rich" gas which already contains more volatile constituents than does the lean gas, the gas temperature in each case being the same. Rich gases contain a larger amount of condensable vapors which admix with the distilled vapors and are condensed therewith.

The tars entrained in rich gases are lower in free carbon content than are the tars entrained in lean gases. Therefore the free carbon content of the residue in the still may be regulated or controlled by the use of rich or lean gases since more or less of the tar entrained in the gases used for distillation will be removed from the gases and be retained in the residue in the still.

In order to take advantage of either rich or lean gas, the coke oven may be equipped with two collector mains, each of which is adapted to be thrown into communication with the uptake pipe from each of the ovens in the battery to which the collector mains are connected thru a system of valves. As an example, during the first of the distillation operation in any one oven, this oven will be thrown into communication with the collector main which is connected directly with recovery apparatus. After the distillation has progressed to the point where lean gases are being given off in this oven, it will be thrown into communication with the other collector main which is in communication with the still.

By the usual rotation of the ovens in a battery of average size, there will at all times be a fairly continuous and uniform production of lean gases, so that the quantity and temperature of the gases passing thru the still will be fairly uniform at all times. Rich gases may, in many cases, be desired for distillation, and can be utilized by my invention.

Depending upon the extent to which the distillation of the tar or tarry oil is carried, substantially only the lighter oils may be removed from the body of tar or oil, leaving a tar or very light pitch in the still. By carrying the distillation further, heavier constituents will be volatilized and recovered from the gases, and a heavier tar or pitch will remain as a residue in the still.

The distillation can be accomplished in numerous ways. For example, a large volume of relatively low temperature gases may be used, or a smaller volume of relatively high temperature

gases, as they come from the ovens, may be used. The tar may also be preheated before being brought into contact with the gases.

The gases escaping from the distilling operation will carry in vapor form the constituents volatilized from the tar and will contain in addition thereto such of the vapor constituents carried by the gases entering the still as have not been removed by contact with the tar or oil being distilled. In the case of hot coke oven gases employed for the distillation of coal tar produced by the coke ovens, the hot gases after the distillation operation will contain uncondensed constituents from the coal distillation as well as added vapor constituents driven off from the coal tar during the distillation.

Higher boiling constituents carried by the hot gases from the ovens may be condensed in the still and the latent heat of condensation absorbed in the distillation operation, in which case condensate from the gases will be blended with the non-volatilized residue of the tar or oil added to the still and drawn off from the still as such. By using coal tar produced at the coke oven plant while it is still hot before it has had opportunity to cool, a saving in heat may be effected.

The gases from the still can be treated for the condensation and recovery of the desirable constituents contained therein as well as for the recovery of ammonia carried thereby. Where only a portion of the gases from the coal distillation apparatus are passed up thru tar or oil in the still, those gases which are enriched by passing thru the tar or oil can be treated in a separate recovery system and the oils condensed therefrom will be a mixture of the oil constituents normally in the gases and those added to the gases during the distillation, whereas the condensate from the remainder of the system will contain only the coal distillation products normal to the gases. The enriched gases can also be treated in the same recovery system with the remainder of the gases produced by the coal distillation.

In a coke oven plant where several batteries of coke ovens are operated, the rich or lean or normal gases from one battery may be employed for distilling tar from the other batteries, or a part of the gases from one battery may be so employed. The gases used in the distillation may be only a portion of the gases collected in the collector main and may be taken off one end of the collector main, or all the gases passing thru the collector main may be utilized e. g. by taking them off the center-box according to the customary practice. A tar or oil, other than a coal-tar product, can be distilled and the condensable constituents recovered in a separate recovery system without contaminating the balance of the coal-tar products produced.

Where the distillation is carried out as a batch operation, the tar or oil is progressively heated by the hot gases and the lighter constituents are progressively removed therefrom until the distillation has been carried to the desired point, after which the operation can be discontinued, and the residue withdrawn, and the still recharged with further tar or oil to be distilled.

Due to enrichment of the gases in clean oil vapors volatilized from the material in the still, the oils removed in the condensers following the still will contain less free carbon and pitch impurities than would oils condensed directly from gases not used for distillation.

In some cases it may be desired to regulate the character of the residue of distillation as respects

free carbon content or as respects the type of oil remaining in or added to it. This may to a greater or less extent be accomplished by using rich or lean or intermediate gases for distillation.

5 Rich gases contain tar with a relatively low free carbon content and they contain also oils of lower average boiling point and lower specific gravity than do lean gases. Rich gases contain a greater amount of tar than lean gases. As the 10 gases get leaner the amount of tar contained in them decreases, the percentage of free carbon in the tar increases, the amount of oil contained in them decreases and its specific gravity and average boiling point increase. Since in the distilling operation more or less of the tar contained in the gases will be retained in the residue and more or less of the contained heavy oils will be condensed and retained in the residue, the character of the residue may to some extent be controlled by choosing the proper gases for distillation. Such gases may be rich, lean or intermediate gases.

The invention will be further described in connection with the accompanying drawings illustrating apparatus embodying the invention and adapted for the practice of the process of the invention, but it is intended and will be understood that the invention is illustrated thereby but is not limited thereto.

30 In the accompanying drawings,

Fig. 1 shows in a somewhat conventional and diagrammatic manner a plan view of a coke oven battery showing apparatus for the distillation of tar by means of the hot coke oven gases;

35 Fig. 2 is a plan view of a modified form of apparatus in which two collector mains are shown with provision for use of rich or lean gases for distillation.

Fig. 3 is an enlarged detail showing in cross-section the relation of two collector mains of Fig. 2 to each other and the coke oven;

40 Figs. 4, 5 and 6 give details of the still shown in Fig. 1.

In the drawings, 5 indicates a coke oven battery 45 with the usual uptake pipes 6, collector main 7, sprays 8, center-box 9 and cross-over main 10. Wet condensers 11 and 12 are provided for condensing tarry oil vapors passing with the gases thru the cross-over main. From the condensers 50 the gases pass thru the pipe 13 and exhaust 14 to the exit pipe 15, from which they may be passed to ammonia saturators or benzol recovery apparatus or other suitable apparatus.

Condensate from the condensers 11 and 12 is 55 drawn off into the decanter 16 from which ammonia liquor is withdrawn into the tank 17 and tar into the receiver 18. Tar and ammonia liquor from the collector main, collecting in the center-box 9, are drawn thru pipe 20 into the decanter 60 from which ammonia liquor is withdrawn into the receiver 21, and tar into the tank 22, or the tar and ammonia liquor may be allowed to run thru the cross-over main 10 and be drawn off at 10' to a decanter not shown.

65 The collector main and goose-necks may be sprayed with tar from 18 thru the pipe 23 or with tar from 22 thru the pipe 24, or with ammonia and/or tar from another source thru pipe 25. One end of the main may be sprayed with tar 70 and one with ammonia liquor by the use of line 24' and valve 33'.

The collector main may be flushed with tar and/or with ammonia liquor thru lines 5' and 8'. By shutting off the sprays 8 and by flushing the main the gases may be held at high temperature

and accumulation of solid hard pitch in the main may be prevented.

The still 26 may be supplied with tar from 22 thru the pipe 27, or tarry oils from the tank 18 thru the pipe 28, or tar or oils from an outside source thru the pipe 29. If necessary, pumps 30 may be provided, as indicated by the reference numerals 30. The feed pipe to the still is equipped with a heat interchanger 31.

Gases from the collector main are led to the still thru the pipe 32. The quantity of gas passing thru the main 32 is controlled by valve means 33 and the exhaust 34. The sprays in the collector main and goose-necks are each provided with a valve so that the spraying at the end of the collector main near the outlet to the pipe 32 may be reduced to a minimum or omitted altogether, and in this manner the temperature of the gases passing thru the pipe 32 may be maintained sufficiently high to produce the desired distillation in the still. The entire system or any of its parts may be adequately insulated. The gases leaving the collector main pass thru the pipe 32 and are caused to bubble thru perforations 34 in the pipe 35 in the bottom of the 95 still.

This still may be of any suitable shape and the gases may be conducted into the contents of the still thru any suitable distributing means submerged in the liquor in the still. Although in 105 the accompanying drawings a single pipe 35 is shown, any number of suitable means may be provided. By making the outlets for the gas small, the surface contact between the gas and the contents of the still is made large and the 110 efficiency of the operation may be increased.

The hot gases, on being brought into contact with the contents of the still, carry off with them the desired volatile constituents of the contents of the still. These mixed gases and vapors pass 115 off from the still thru the pipe 36 thru which they may be passed to any suitable condensing means such as the condensers 37 and 38, in which case they will be led thru pipe 39 to the pipe 15, or they may be by-passed thru the pipe 40 and conveyed to the condensers 11 and 12 or other suitable condensing means thru the pipe 41.

Condensate from the condensers 37 and 38 is collected in the decanter 42. Two separate oil fractions may be collected by drawing off the 125 condensate from one condensing section thru line 28' to a decanter not shown and drawing off the other to decanter 42. Oil from 42' may be supplied to the collector main or still as shown. Baffle means (not shown) may be provided at the 130 gas outlet from the still to prevent liquor entrained in the gases from passing over to the condensers.

The still may be operated as a batch operation or as a continuous process. In the latter case, 135 the quantity of material admitted to the still for distillation will be regulated by the valve 43, and the quantity of residue drawn off thru the pipe 44 to the receiver 45 will be regulated by the valve 47. The contents of the still may be 140 reduced to a high melting point pitch or by controlling the extent of the distillation a heavy tar or light pitch may be produced in the still.

In the apparatus shown in Fig. 2, the parts of the equipment have been made to correspond 145 as far as possible with the corresponding parts of Fig. 1 as indicated by the numerals. 305 represents the coke oven battery with the two collector mains 307 and 307'. The cross-over main 310 leads to condensers 311 and 312. From 150

- the collector main 307, the gases are conducted thru the main 332 into the still 326 and from thence by the pipe 336 to the conductors 337 and 338 or thru the by-pass 340. Residue from the still is drawn off thru the pipe 344 into the storage receptacle 345. Tarry oils are drawn off the condensers 311 and 312 into the decanter 316, from which ammonia liquor is drawn off into the receiver 317 and tarry oil into 318. From 318 the tarry oil may be pumped by pump 331 thru the heat interchanger 331' into the still. Instead of supplying the still with tarry oil from this source, tar or oil from any outside source may be supplied thru the pipe 370, or tar from either of the collector mains may be drawn off thru the center-boxes 309 and 309' and the pipes 371 and 372 to the decanters 373 and 374 from which ammonia liquor is drawn off into the storage tank 375, and the tar which is collected in the two receivers 376 and 377 may be supplied to the still thru the pipes 378 and 379, respectively. When it is desired to spray tar without ammonia liquor into the gases going to the still the tar may be supplied thru the lines 380 and the sprays connected thereto. The collector main may be flushed with tar and/or ammonia liquor thru lines 305' and 376'. By shutting off the sprays the gases may be held at high temperatures, and by flushing the main accumulation of solid hard pitch may be prevented. The character and quantity of the residue withdrawn from the still and of the clean oils condensed from the enriched gases leaving the still is dependent upon many factors, such as the quantity and temperature of the gases, which depend to some extent upon the spraying of the gases in the collector main and also upon the character and quantity of tar or oil supplied to the still. Controllable variables permit regulation of the process to produce the desired tars or pitches from the still and oils of the desired quality from the condensers.
- I claim:
1. The method of distilling heavy hydrocarbon material in liquid form by the heat of hot coal distillation gases resulting from the distillation of coal, which comprises separately collecting the gases from a controlled period of the coal distillation operation, bubbling them at a temperature above the dewpoint of oil vapors therein up thru a body of the hydrocarbon material, thereby volatilizing constituents of the material and producing a pitch residue of regulated free carbon content, and thereafter cooling the resulting gases and vapors to condense oils therefrom which contain both distillate oils and oils condensed from the coke oven gases.
  2. The method of distilling heavy hydrocarbon material in liquid form by the hot coal distillation gases at a coal distillation plant, which comprises causing hot coal distillation gases from the coal distillation apparatus of the plant at a temperature above the dewpoint of oil vapors therein to bubble up thru a body of the hydrocarbon material, whereby constituents thereof are volatilized by the heat of the gases and pitch residue is produced, continuously adding fresh hydrocarbon material thereto and withdrawing pitch residue therefrom, and cooling the gases and vapors resulting from the distillation to condense oils therefrom, which contain both distillate oils and oils condensed from the coal distillation gases.
  3. The method of distilling heavy hydrocarbon material in liquid form, which comprises causing fresh hot coal carbonization gases to bubble thru the hydrocarbon material so as to heat the material and effect substantial cooling of the gases, agitate it and effect the removal of volatile matter therefrom, and cooling the resulting gases to condense distillate oils therefrom.
  4. The method of distilling tar to pitch, which comprises causing fresh hot tar-laden coke oven gases to bubble up thru a substantial depth of a body of tar while distilling it, thereby imparting heat to the tar, facilitating the removal of oil vapors from the tar, removing entrained tar particles from the gases and incorporating them in the pitch residue formed, and cooling the resulting gases to condense distillate oils therefrom.
  5. The method of operating a coke oven battery comprising a plurality of ovens in which coal is being distilled, which comprises withdrawing and mixing hot fresh coal distillation gases from a plurality of the ovens, causing the hot mixed gases to bubble up through a substantial depth of a body of tar thereby distilling off volatile oils from the tar and partially cooling the gases, then further cooling the gases to condense therefrom oils originally present in the gases and oils distilled off from the tar.
  6. The method of operating a coal distillation plant comprising a plurality of ovens or retorts in which coal is being distilled, which comprises collecting the hot coal distillation gases from a portion of the ovens or retorts of the plant and cooling them to separate tar, collecting at least a portion of the tar as a body thereof, collecting hot coal distillation gases from other ovens of the plant and bubbling them while still at a high temperature up through a substantial depth of said body of tar so as to distill the tar by the heat of said gases.
  7. The method of distilling heavy hydrocarbon material in liquid form and containing volatile constituents, which comprises causing fresh hot coal carbonization gases while still at a temperature above about 300° C. after their production to bubble through a substantial depth of the hydrocarbon material thus distilling off volatile constituents from the hydrocarbon material.
  8. The method of distilling dehydrated tar at a coal distillation plant having a plurality of ovens or retorts in which coal is being distilled, which comprises causing a portion of the fresh hot coal carbonization gases from the plant to bubble through the dehydrated tar so as to heat the tar and effect substantial cooling of the gases, agitate it, and effect the removal of volatile matter therefrom, cooling the resulting gases to condense distillate oils therefrom, and uniting the gases from which the oils have been separated with other coal distillation gases from the plant.

STUART PARMELEE MILLER
